UNITED STATES PATENT OFFICE.

GEORGE ADOLPH STEINER, OF SALT LAKE CITY, UTAH, ASSIGNOR TO AMERICAN LINEN SUPPLY COMPANY, OF SALT LAKE CITY, UTAH, A CORPORATION.

TOWEL-CABINET.

1,287,783.

Specification of Letters Patent.

Patented Dec. 17, 1918.

Application filed January 3, 1917. Serial No. 140,344.

To all whom it may concern:

Be it known that I, GEORGE A. STEINER, a citizen of the United States, resident of Salt Lake City, county of Salt Lake, State of Utah, have invented certain new and useful Improvements in Towel-Cabinets, of which the following is a specification.

The object of my invention is to provide a cabinet in which a bundle or package of 10 towels can be easily and quickly placed and from which a user can readily withdraw the towels, one at a time.

A further object is to dispense with followers and the like, which create too great 15 a pressure on the towels and interfere with the one-by-one withdrawal thereof.

A further object is to provide a cabinet of simple, economical construction, which will occupy but little space on the wall and 20 can be manufactured for a comparatively small expense.

Other objects of the invention will appear from the following detailed description.

The invention consists generally in various 5 constructions and combinations, all as hereinafter described and particularly pointed out in the claims.

In the accompanying drawings forming part of this specification,

0 Figure 1 is a perspective view of a towel cabinet embodying my invention.

Fig. 2 is a detail sectional view, showing the manner of mounting the towel stringer in the cabinet,

5 Fig. 3 is a detail view, showing the means for supporting the towel stringer on the rear wall of the cabinet,

Fig. 4 is a detail view showing a means for connecting the end of the stringer to the cabinet,

Fig. 5 is a perspective view of a modified form of cabinet,

Fig. 6 is a similar view, showing the spring arms mounted on the back of the cabinet near one end,

Fig. 7 is a perspective view showing a pair of arms, one on each side of the cabinet and with the rigid rod of the stringer omitted,

Fig. 8 is a detail sectional view, showing the preferred manner of connecting the stringer to the cabinet when the rod is omitted,

Figs. 9 and 10 are detail views of the loops provided on the towels to receive the stringer,

Fig. 11 is a detail view, showing a modified form of rod on the end of the stringer.

In the drawing, 2 represents the back of the cabinet and 3 the side walls or wings thereof, projecting outwardly from the back in substantially parallel relation. The lower

ends of these wings are cut away so that when a bundle of towels is suspended between them the lower portion of the towels will be visible and in position to be easily grasped by the person desiring to use one.

In the back of the cabinet a vertical recess 4 is provided, having guard rails 5 on each side thereof and a plate 6 is secured over said recess and provided with a vertical slot 7, which registers with the recess. A tube

8 has a flange 9 at one end and is adapted to slip into the recess 4 and slide down into the slot 7, the edges of the slot engaging the flange 9 and holding the tube in a position

projecting outwardly and downwardly, as indicated in Fig. 2 of the drawing. The towels 10 have gromets 11 therein, preferably in the center at one end, and the tube

is threaded through these, the weight of the towels being supported by the tube when it is inserted into the socket in the back of the cabinet. A stringer 12 of wire or other suitable material is provided, on one end of

which the tube 8 is mounted, while the opposite end is threaded through the towels 85 at the laundry and has an eye to receive the padlock 13, which prevents the towels from being removed when the device is in use.

This flexible stringer hangs down below the cabinet, as indicated in Fig. 1, and a snap hook 14 is preferably provided to engage the padlock and is fastened to the cabinet by suitable means, such as the screw eye 15. A head may be formed on the end of the stringer to prevent the tube from being 95 separated therefrom.

In practice, the towels will slide freely on the tube, which is preferably inclined forwardly and downwardly, as indicated in Fig. 2, so that when a person grasps the 100 outer towel to remove it from the cabinet, its upper end will slide freely on the tube

until it reaches the outer end thereof and will then drop down on the stringer as a guide to a point where it can be conveniently 105 used and, after such use, the towel, when dropped, will slide down on the stringer to a position under the cabinet and remain sus-

pended in that position until all the towels have been used and the bundle is removed from the cabinet for the substitution of a clean lot.

- 5 It will be noted that the weight of the towels is carried by the tube, which has sufficient rigidity to support a package of towels, hence the pull of the soiled towels on the stringer will not have any effect on the 10 removal of a clean towel from the cabinet.
- To hold the towels in place and facilitate their one-by-one removal, I prefer to provide curved arms 16 formed preferably by bending the ends of a rod 17 forwardly and 15 downwardly, said rod having bearings near said arms in a frame 18 that is secured by suitable means to the back of a cabinet. A spring 19 is mounted on said rod and tensioned to hold the curved arm 16 against the 20 outer face of the bundle of towels with a yielding pressure, and this pressure is at one point only on each side of the center of the towels and thereby distinguishes from a follower sometimes used in devices of this kind 25 for pressing the towels together. It has been found, however, that a follower exerts pressure over such a large area that there is considerable tendency for several towels to stick together and be withdrawn 30 from the cabinet, while by having pressure arms bearing only on a small surface of the towels, this tendency is entirely avoided, a quick jerk, such as a person usually would exert on a towel, withdrawing the forward 35 one from beneath the arms without disturbing the other towels of the bundle. When all the towels have been withdrawn, the attendant will lift the tube out of its socket, detach the lower end of the stringer from its 40 supporting hook, and the bundle of soiled towels may then be substituted for a clean lot and the change made easily and expeditiously.
- In Fig. 5 I have shown a cabinet having 45 a rear wall 20, side walls 21 and a lower wall or shelf 22. The tube for the stringer, instead of passing through the center of the towels, is inserted through eyelets or grommets 23 provided in one corner, a socket 24 being mounted in the corresponding corner 50 of the cabinet into which the flanged end of the tube, corresponding to the one previously described, is inserted. The other end of the bundle of towels rests upon the bottom or shelf 22 of the cabinet and the adjacent wall 21 preferably has a hand-hole opening 24' to permit a person to grasp the end of the foremost towel and remove it 55 from the cabinet. A loop 25 is preferably mounted at 26 on the wall 21 and a spring 60 27 is mounted on said loop for yieldingly holding it against the ends of the towels. This loop is preferably located near the upper corner of the towels opposite the location of the tube and stringer.

In Fig. 6 a similar cabinet is shown, with spring-pressed arms 28 mounted on brackets 29 which project forwardly from the back of the cabinet, instead of being mounted on the end wall, as in Fig. 5. I show also a strip of sand paper or emery cloth 30 mounted on the back of the cabinet, between which and the spring-pressed arms the towels are held, this strip forming a friction surface for holding the towels in place, particularly when near the bottom of the pile. In other respects this cabinet is substantially the same as the one shown in Fig. 5; that is, as far as the tube and stringer are concerned, and their position 75 in the cabinet and the towels hang vertically in the cabinet, resting on one longitudinal edge which contacts with the floor or shelf at the bottom of the cabinet.

In Fig. 7 I have illustrated another type, 80 consisting of a back 31, side walls 32 and 33 and a bottom 34. This bottom and the adjacent wall are cut away at 35 to expose the lower corner of the bundle of towels and permit them to be grasped, one by one, by 85 the user. Spring-pressed loops 36 are mounted on the walls 32 and 33, preferably near the top of the cabinet, and bear on the bundle of towels with a yielding pressure.

I prefer to provide the towels with loops 90 37, preferably metallic, on one end of the towels near the center, so that when the towels are arranged in a pile these loops will all coincide with one another, and are of sufficient size to receive a flexible stringer 1 38 on one end of which a button or washer 39 is mounted for entering a socket 40 in the rear wall of the cabinet, the other end of the stringer being attached to the cabinet in substantially the same manner as shown in Fig. 1. 4. In this cabinet the towels are supported entirely by the bottom shelf 34, the flexible stringer having no supporting function for the clean towels, but merely serving as a guide and a means to prevent the towels 1 from being stolen, one-by-one, from the cabinet. Each of the cabinets is preferably provided with a hook 41 and a flexible connection 42, so that the wall of the cabinet will engage the spring-pressed arms or loops and hold them in their retracted position, while the towels are being placed in the cabinet.

Instead of using the loops 37 for stringing the towels, I may employ one as indicated at 43 in Fig. 10, the loop being elongated instead of round, but preferably fastened to the towel in substantially the same manner as shown in Fig. 9. The mounting of the loops in this way on the towels has an advantage in providing a larger usable area for each towel than where an eyelet or grommet is placed in the end or corner of the towel itself, and towels equipped with these loops, which are entirely outside the edge of

the towels, may be made somewhat smaller than those towels where gromets or eyelets are inserted.

In place of the tube through which the stringer is threaded, I may provide a wire rod 44 to the outer end of which the flexible stringer 38 is attached. The opposite end of this rod is preferably curled to form a flat flange or washer by making a series of convolutions in the rod, one within the other, and in the same plane and adapted to slip into the slot in the socket in the back of the cabinet, as described with reference to the previous figures.

15 I have shown the cabinets provided with side walls or wings, but these may be omitted, the spring arms being preferably mounted at the top of the rear wall and overhanging the upper portion of the towels, 20 bearing lightly thereon with sufficient pressure to hold the towels in place but allowing the foremost one to be readily removed with a slight twitch or pull.

I claim as my invention:

25 1. The combination, with a cabinet comprising a rear wall against which the bundle of towels is placed, said rear wall having a socket formed therein, of a stringer having a washer or button to enter said socket and 30 on which stringer the towels of the bundle are strung, the other end of the stringer having means for connection with the cabinet, and spring-pressed arms positioned to bear on the towels and exert pressure for 35 a limited area thereon, whereby the towels may be removed, one by one, from the cabinet, the foremost towel being pulled out without disturbing the other towels.

2. A towel cabinet having a rear wall, a 40 flexible stringer mounted at one end on said wall and having means for connection at its other end with the lower portion of the cabinet and hanging loosely in front of the cabinet to support the used towels as they 45 are drawn forwardly from the cabinet and released, a frame mounted on said rear wall and projecting outwardly therefrom above the towels, and spring-pressed arms carried by said frame and having outwardly and 50 downwardly curved portions to bear on the outer towel of the bundle for yieldingly holding it in place thereon.

3. A towel cabinet having a rear wall, a 55 flexible stringer mounted thereon at one end and having an inflexible section at said end for supporting the towels vertically in the

cabinet, the other end of said stringer having means for attachment with a support and forming a flexible loop in front of the cabinet to receive the soiled towels as they 60 are withdrawn therefrom, one at a time, arms supported on said rear wall and forwardly and downwardly curved to bear upon the outer towel of the bundle, a spring for holding said arms with a yielding pressure 65 against the outer towel, and means for holding said arms out of contact with the towels against the tension of said spring.

4. A towel cabinet comprising a rear wall having a socket formed therein, a tube having 70 a head formed on one end to enter said socket, said tube being forwardly and downwardly inclined and adapted to support a bundle of towels placed one against the other, means forming a continuation of said 75 tube on which the soiled towels are carried when removed from said tube, and means pressing lightly on the outer towel of the bundle and permitting said outer towel to be pulled off the bundle without disturbing 80 the other towels.

5. The combination, with a wall having a socket therein, of a rigid member having a head to enter said socket, said member projecting outwardly and downwardly therefrom and forming a support for a bundle of towels, a flexible stringer forming a continuation of said rigid member and whereon the towels are suspended when removed from said member, and means bearing on 90 the outer towel of the bundle for holding it in place but permitting it to be readily detached from the bundle.

6. The combination, with a cabinet having back and side walls and an open front, 95 of a stringer having means for mounting it on the rear wall of the cabinet and including a rigid rod and a wire forming a continuation thereof, said rod forming a support for the towels suspended vertically 100 thereon, and spring arms mounted on the wall of said cabinet to bear on the upper portions of the towels and yield when the lower portion of a towel is grasped to allow it to be moved from its normal position on 105 said rod to its using position on said wire.

In witness whereof, I have hereunto set my hand this 26th day of December, 1916.

GEORGE ADOLPH STEINER.
